UNITED STATES PATENT OFFICE.

OLIN C. KNIGHT, OF BOSTON, MASSACHUSETTS, ASSIGNOR TO UNITED DRUG COMPANY, OF JERSEY CITY, NEW JERSEY, A CORPORATION OF NEW JERSEY.

DESIGN FOR AN ADVERTISING DEVICE.

No. 38,227.

Specification for Design.

Patented Sept. 4, 1906.

Application filed July 19, 1906. Serial No. 326,941. Term of patent 3½ years.

To all whom it may concern:

Be it known that I, OLIN C. KNIGHT, a citizen of the United States, and a resident of Boston, in the county of Suffolk and State of Massachusetts, have invented a new, original, and ornamental Design for an Advertising Device, reference being had to the accompanying drawing, which shows an elevation of my design.

I claim—
The ornamental design for an advertising device as shown.

OLIN C. KNIGHT.
